[57] CLAIM

The ornamental design for a needle protector, as shown.

DESCRIPTION

FIG. 1 is a perspective view of a needle protector showing my new design with the hinged cap in closed position;

FIG. 2 is a front elevational view thereof;

FIG. 3 is a side elevational view thereof, the opposite side elevational view being identical;

FIG. 4 is a rear elevational view thereof;

FIG. 5 is a top plan view thereof;

FIG. 6 is a bottom plan view thereof;

FIG. 7 is a top plan view thereof, with the hinged cap in open position;

FIG. 8 is a cross-sectional view thereof, taken along the line 8—8 of FIG. 9; and,

FIG. 9 is a perspective view thereof, with the hinged cap in open position.

FIG. 1

FIG. 9

FIG. 4
